(57) **CLAIM**

The ornamental design of a child safety seat for motor cars, shown and described.

DESCRIPTION

FIG. 1 is a perspective view of a child safety seat in accordance with the present invention;

FIG. 2 is a front elevational view of the child safety seat of FIG. 1;

FIG. 3 is a rear elevational view of the child safety seat of FIG. 1;

FIG. 4 is a side elevational view of a first side of the child safety seat of FIG. 1;

FIG. 5 is a side elevational view of a second side of the child safety seat of FIG. 1;

FIG. 6 is a top plan view of the child safety seat of FIG. 1; and,

FIG. 7 is a bottom plan view of the child safety seat of FIG. 1.

1 Claim, 7 Drawing Sheets
